UNITED STATES PATENT OFFICE.

BELLE L. JOHNSON, OF CINCINNATI, OHIO.

SOAP AND METHOD OF MAKING SAME.

SPECIFICATION forming part of Letters Patent No. 712,069, dated October 28, 1902.

Application filed December 21, 1901. Serial No. 86,746. (No specimens.)

To all whom it may concern:

Be it known that I, BELLE L. JOHNSON, a citizen of the United States, residing at Cincinnati, in the county of Hamilton and State of Ohio, have invented certain new and useful Improvements in Soap and the Method of Making the Same, of which the following is a specification.

The object of my invention is to provide a soap which will not only have exceptional cleansing qualities, but will make fast instead of dissipating the colors in colored washable fabrics; and my invention consists in the soap and the method of making the same herein-after described and claimed.

My improved soap is composed of coagulated turpentine and pure white soap, consisting, preferably, of from twenty-five to thirty-five parts of oil or spirits of turpentine and sixty-five to seventy-five parts of pure white soap, sufficient water being used to reduce the soap to a semifluid state. The coagulated turpentine is prepared by heating turpentine until incipient boiling sets in, then adding finely-divided white soap until when tested by cooling a gum-like transparent mass is produced. This will require approximately one part of soap to fifteen parts of turpentine. The white soap is prepared by stirring

together finely-divided white soap and boiling 30 water, preferably in the proportion of four parts of soap to one part of water. This should produce a semifluid sticky mass. The ingredients thus prepared are then mixed, stirred thoroughly, and poured into molds.

35

It is obvious that limited quantities of other non-deleterious ingredients may be added for scenting, coloring, &c., without departing from the spirit of my invention.

I claim as my invention—

40

1. The herein-described method of making soap, consisting in heating oil or spirits of turpentine until incipient boiling sets in, mixing the heated turpentine with a small quantity of white soap, reducing a quantity of white 45 soap to a semifluid mass, and mixing the prepared turpentine and the prepared soap, substantially as and for the purpose specified.

2. The herein-described compound, consisting of oil or spirits of turpentine and white 50 soap in substantially the proportion of three parts of turpentine to seven parts of soap, as and for the purpose specified.

BELLE L. JOHNSON.
